UNITED STATES PATENT OFFICE.

GEORGE E. PURPLE, OF LA GRANGE, ILLINOIS, ASSIGNOR TO FLEXIBLE STEEL LACING COMPANY, OF CHICAGO, ILLINOIS, A CORPORATION OF ILLINOIS.

BELT-LACING DEVICE.

Application filed May 25, 1927. Serial No. 194,019.

This invention relates to improvements in belt lacing device.

One object of my invention is to provide a simple, efficient and relatively inexpensive device for applying lacings to belts of any width.

Another object of my invention is to provide a hand-operated device of the type indicated in the preceding paragraph adapted for belts or aprons up to ten feet or even more in width, such as are commonly used in laundry ironers and the like.

More specifically, an object of my invention is to provide a belt lacing device adapted for different width belts or aprons, wherein the holder for the belt lacing and the anvil associated therewith are made in unit lengths adapted to be so assembled as to provide for any desired width of belt or apron and with which is associated a relatively small, traveling striker block, adapted to be struck by a hammer or other suitable tool, whereby the desired length of belt lacing corresponding to the full width of the belt may be clinched by shifting the striker block from point to point along the device and striking the same with a hammer, all in a quick, expeditious manner.

Other objects of the invention will more clearly and fully appear from the description and claims hereinafter following.

In the drawing forming a part of this specification, Figure 1 is a top plan view of a belt lacing device showing my improvements embodied therein. In this view, the device is broken off at one end and also broken away intermediate its ends in order to illustrate the device on a suitable scale. Figure 2 is a vertical, transverse, sectional view corresponding to the section line 2—2 of Figure 1 and illustrating the position of the striker block just as it engages the belt lacing. In this view, portions of the base are broken away to accommodate the figure on the sheet. Figure 3 is a view similar to Figure 2, but illustrating the position of the striker block when the belt lacing is partially clinched to the belt or apron. Figure 4 is a front elevational view of the striker block detached. Figure 5 is a top plan view of a form of belt lacing usable with my improved device. Figure 6 is a plan view of a portion of a belt or apron

showing the belt lacing applied thereto. And Figure 7 is a view similar to Figure 3 showing the lacing fully clinched and the striker block in its lowest position.

In carrying out my invention, I preferably employ a suitable base or standard indicated by the reference character A which, in the form shown, may be a section of rolled channel inverted so as to present the web of the channel uppermost and thus provide a horizontal bed or support for the other parts. Said base A will be made of suitable length corresponding to the maximum width of belt or apron for which the device is to be used, this length frequently being as much as ten feet and, of course, may be more.

Secured to the upper side of the base A, as by the bolts 10, is an elongated support B, which will also be made of a length corresponding approximately to the length of the base A. Said support B preferably comprises a barlike element, which is suitably machined so as to provide a flat bottom 11; a vertical inner face 12 and an outer vertical face 13. On the top, the bar support B is provided with an elongated guideway 14 near the inner edge thereof and a relatively wide elongated recess 15 rectangular in cross-section, for the purposes about to be described. Between the guideway 14 and the recess 15, the support B is thus left with an upstanding wide rib section 16, to which the lacing holder is secured.

The belt lacing holder, indicated generally by the reference character C, consists of a plurality of unit sections 17—17, at their adjacent ends abutted as indicated at 18 in Figure 1, said unit sections being secured to the rib 16 by a series of machine screws 19—19. Each unit 17 will preferably be made of about one foot length, thus adapting it for economical manufacture and will be comprised preferably of brass. In this manner, it is evident that a holder of any desired length may be built up, corresponding to the maximum width of the belt or apron to be operated upon and further, should any part of the holder become injured, it can readily be replaced by another unit length of like construction. Each unit section 17 of the lacing holder has the front

face thereof beveled as indicated at 20 and the front edge slotted or milled so as to provide a plurality of substantially triangular recesses 21 separated by triangular partitions 22. In this manner, the prongs 23—23 of the belt lacing are adapted to be received within the respective spaces 21 and the lacing held by means of a holding pin 124, which is extended lengthwise of the lacing 10 holder and passed through suitable aligned holes in the partitions 22. As will be understood by those skilled in the art, the lacing may be supplied in suitable lengths and one well known form of such lacing is 15 indicated in the drawing.

In the manufacture of the holder unit sections and in assembling the same on the support B, it is essential that the units be accurately aligned and the milling of the 20 slots or recesses to receive the lacing be uniform and to this end the unit sections 17 are each provided with a shallow groove 24 on the underface thereof. Said groove 24 is used as a gauge for the milling of the 25 slotted edge of the holder and also the grooves 24 of the assembled unit 17 receive a rod 25 extended lengthwise thereof and which accurately fits the grooves 24 so that, when the units are thus assembled with the 30 rod 25 in place, they are accurately aligned and may then be secured in place by tightening the screws 19. With this arrangement, it is evident that I am not dependent upon the accuracy of location of the tapped 35 holes for securing screws 19 which may vary slightly under manufacturing conditions.

As will be evident from an inspection of Figures 2 and 3, the holder is of a width corresponding substantially to the horizontal width of the rib 16, thus presenting the most advanced part of the holder to a point in line with the front vertical edge of the rib 16. Disposed in the elongated recess 15 is the anvil of my improved device, said 40 anvil being indicated generally by the reference character D. The anvil is comprised preferably of a plurality of unit lengths 26—26 of case-hardened or otherwise suitably hardened steel adapted to withstand 45 the blows incident to the clinching of the belt lacing. The anvil sections 26 are of a depth slightly greater than the depth of the recess 15 and the upper faces of the anvil sections 26 are beveled downwardly and 50 inwardly along their inner edges as indicated at 27, the innermost edges of the beveled portions terminating substantially flush with the lower surface of the holder C, for the purpose hereinafter described. 55 By making the anvil in unit sections corresponding preferably in length to the unit sections of the holder, it will be seen that I can make the device of any desired length and also am enabled to effect replacements 60 at minimum cost.

Cooperable with the holder and anvil described in the preceding, is a striker block indicated generally by the reference character E. Said striker block E is preferably made of a length slightly less than half of 70 the length of the unit sections of the lacing holder and is provided on the top with a rounded striking surface 28, against which the hammer impinges when clinching the lacing. The block E is provided with two 75 rearwardly extended curved arms 29—29, suitably apertured as indicated at 30 to receive the ends of a heavy pin 31, which is mounted in a suitable bearing 32 provided in a carrier indicated by the reference character F. The pin 31 is retained in position by any suitable means such as the cotters 33—33. As will be evident from an inspection of the drawing, the arms 29 straddle the carrier F and the block E is thus adapted to 80 swing through an arc of approximately 180° with reference to the carrier F. The block E is provided along its front edge with a depending suitably hardened section 34, the bottom face 35 of which affords a striking 85 face so located as to engage the upstanding prongs of the belt lacing as indicated in Figure 2. The innermost portion of the striking face 35 is beveled or slightly rounded in a direction opposite to the beveled portion 27 of the anvil so that, when the striker block E is in its lowermost position and at which time the lacing is clinched to the belt or apron 36, the two beveled faces converge in a direction away 90 from the lacing holder. The arrangement of the striking beveled faces of the striker block and anvil is an important feature particularly when the device is used in connection with comparatively thin belts or aprons, 95 such as canvas, and correspondingly small-sized belt lacings. It will also be noted, by reference to Figure 7, that the portions of the striking faces of the anvil and striker block which are remote from the holder, will 100 be parallel or approximately parallel at the final clinching operation. With this arrangement of oppositely beveled striking faces and parallel faces, the prongs of the belt lacing may be properly clinched in the 105 belt or doubled over end of the apron and the outer faces of the prongs brought flush with the outer faces of the belt or apron without danger of the prongs of the lacing being forced so closely together as to tear 110 or shear the fabric. Further, the parallel portion of the faces will engage the apron or belt outwardly of the lacing proper and hence the downward movement of the striking block will thus be limited by the belt or apron. In this manner, proper application 115 of the lacing without danger of deforming the usual hinge-pin receiving portion of the lacing or danger of tearing or injuring the fabric or apron, is positively assured. 120

125

130

To facilitate longitudinal movement of the striker block E along the lacing, the ends of the striking face thereof are oppositely upwardly beveled as indicated at 5 37-37 in Figure 4, the beveled faces 37 riding smoothly over the prongs of the lacing as will be obvious. The carrier F is longitudinally slidably mounted with respect to the support B by means of an overhanging 10 flange 38, which fits in the guideway 14 and a detachable plate 39 on the bottom thereof, which has a projecting section 39a received in a longitudinal rabbet 40 provided on the bottom of the support or bar B. As will be 15 understood, the plate 39 is secured to the carrier F by suitable screws 41 and the carrier is slipped endwise onto the support B and may be adjusted to any point thereon.

In the operation of my device, a suitable 20 length of belt lacing is inserted in the holder and secured therein by the pin 24 in the manner indicated best in Figure 2. The edge of the belt or apron is then presented to the holder between the two sets of prongs 25 of the lacing as indicated in the same view and then the striking block E is hammered down preferably beginning at one side of the belt and working gradually along the entire width of the belt until the entire length of 30 lacing is applied. The pin 24 is then removed and the apron or belt with the lacing attached also removed.

In the drawing, I have illustrated one 35 specific form of belt lacing and to which the term "lacing" is technically correctly applied. However, as will be obvious to those skilled in the art, other forms of belt 40 lacings or fasteners such as a series of individual hooks or staples may be used with my improved device and I employ the terms "lacing" or "belt lacing" in the appended claims, broadly, to include any type of belt lacing or fastening.

From the preceding description taken in 45 connection with the drawing, it will be evident that my improvements may be manufactured at comparatively small cost and the device made for any suitable width of belt or apron. The lacing may be applied readily and without the aid of any special tools, the only tool required being a hammer or 50 the equivalent.

Although I have herein shown and 55 described the preferred manner of carrying out my invention, I am aware that various changes and modifications could be made without departing from the spirit of the invention, and all such changes and modifications are contemplated as come within 60 the scope of the claims appended hereto.

I claim:

1. In a belt lacing device, the combination with a support having a lacing holder thereon and an anvil extending lengthwise of and 65 adjacent to said holder; of a carrier mov-

able lengthwise of said support in definite relation to said holder; and a striker block movably attached to said carrier and adapted to be positioned over the anvil and lacing held in the holder at any point therealong. 70

2. In a belt lacing device, the combination with a support having a lacing holder thereon and an anvil extending lengthwise of and adjacent to said holder; of a carrier slidably mounted to move lengthwise of said support in definite relation to said holder; and a striker block movably attached to said carrier and adapted to be brought to position over said anvil in cooperative relation thereto at any point therealong. 75

3. In a belt lacing device, the combination with a support having a lacing holder thereon and an anvil extending lengthwise of and adjacent to said holder; of a carrier movable lengthwise of said support in definite relation to said holder; and a striker block pivotally attached to said carrier and having a striking face adapted to be brought to cooperative position relative to said anvil at any point therealong. 80

4. In a belt lacing device, the combination with a support having a lacing holder thereon and an anvil extending lengthwise of and adjacent to said holder; of a carrier slidably mounted lengthwise of said support; and a striker block pivotally attached to said carrier and movable in unison therewith, said striker block having a striking face adapted to be brought into cooperative relation with said anvil at any point along 90 the latter. 95

5. In a belt lacing device, the combination with an elongated support; of an elongated belt lacing holder fixedly mounted on and extending lengthwise of said support, said holder comprising a plurality of unit sections abutted end to end; an elongated anvil extended lengthwise of and adjacent the holder; and means cooperable with said anvil and longitudinally movable above the 100 abutted sections of said support for clinching the belt lacing held in said holder. 110

6. In a belt lacing device, the combination with an elongated support; of a lacing holder extended lengthwise of and fixedly 115 secured to said support, said holder comprising a plurality of unit sections abutted end to end and having aligned slots therein; means fitting within said slots and extending the length of said unit sections to thereby maintain their alignment; an elongated anvil disposed in front of and adjacent said holder; and means cooperable with said anvil and longitudinally movable above the 120 abutted sections of said support for applying 125 a belt lacing held in said holder.

7. In a belt lacing device, the combination with an elongated support; of a lacing holder extended lengthwise of said support and comprised of a plurality of unit sections 130

abutted end to end, said sections having aligned slots; means fitting within said slots and extending from one unit to the next unit to thereby maintain their alignment; an anvil extending lengthwise of said holder and adjacent thereto, said anvil comprising a plurality of aligned unit sections abutted end to end; and means, adjustable lengthwise from section to section of the support, 10 operable with the aligned sections of said anvil, to apply belt lacing secured in said holder.

8. In a belt lacing device, the combination with a support having a lacing holder; of an anvil disposed in operative position relative to said holder, said anvil having its striking face adjacent the holder beveled; and a pivotally mounted striking block 20 operable with said anvil, said block having its striking face beveled opposite to the bevel of the anvil whereby, as the two said striking faces are brought toward each other to clinch a belt lacing therebetween, said faces converge in a direction away from the holder.

9. In a belt lacing device, the combination with a horizontally disposed support having a lacing holder mounted thereon; of an anvil 30 extending lengthwise of the holder adjacent the edge of the latter, said anvil having its upper face disposed partly in a horizontal plane and partly in a plane inclined downwardly toward the holder; of a striking block pivoted rearwardly of the holder and having a striking face adapted to cooperate with that of the anvil, the striking face of said block being also inclined oppositely to the inclined portion of the anvil.

10. In a belt lacing device, the combination with a support provided with an anvil; of a lacing holder also mounted on said support; a carrier slidably lengthwise of the support and holder; and a striker block pivotally attached to said carrier, said block 45 having a relatively elongated striking face, the latter being beveled at its ends in directions away from the anvil, when the block is in cooperative position relative to the anvil.

50 11. In a belt lacing device, the combination with an elongated base; of an elongated supporting bar secured to said base, said supporting bar having a recess extending lengthwise thereof; an anvil disposed in said recess and comprised of a plurality of unit sections abutted end to end; an elongated holder mounted on said supporting bar in cooper-

ative relation with said holder comprising a plurality of unit sections abutted end to end; a carrier slidably mounted on said supporting bar and adapted to be shifted to any position therealong; and a striking block pivotally attached to said carrier and adapted to be brought opposite the anvil to cooperate with the latter in clinching a fastener. 60 65

12. In a belt lacing device, the combination with an elongated base; of an elongated supporting bar secured to said base, said supporting bar having a recess extending lengthwise thereof; an anvil disposed in said recess and comprised of a plurality of unit sections abutted end to end; an elongated holder mounted on said supporting bar in cooperative relation with said anvil, said holder comprising a plurality of unit sections abutted end to end; a carrier slidably mounted on said supporting bar and adapted to be shifted to any position therealong; and a striking block pivotally attached to said carrier and adapted to be brought opposite the anvil to cooperate with the latter in clinching a fastener. 70 75 80

13. In a belt lacing device, the combination with an elongated support; of an elongated belt lacing holder mounted on and extending lengthwise of said support, said holder comprising a plurality of interchangeable unit sections abutted end to end in straight alignment; and cooperable striking and anvil means operatively associated with said holder for clinching a belt lacing held therein, said striking means being movable relatively to the aligned sections of said holder. 90 95

14. In a belt lacing device, the combination with a support having a lace holder; of an anvil disposed adjacent and at the front side 100 of said holder; and a pivotally mounted striking block cooperable with said anvil, said block and anvil having striking faces which, at the portions nearest the holder, are oppositely beveled and converged in a direction away from the holder and outwardly of the beveled portions are disposed substantially parallel, when the striker block is in its extreme clinching position. 105

In witness that I claim the foregoing I have hereunto subscribed my name this 19th day of May, 1927. 110

GEORGE E. PURPLE.
